UNITED STATES PATENT OFFICE

169,243

PUNCHING BAG

William E. Doherty, Chicago, Ill.

Application October 8, 1952, Serial No. 21,761

Term of patent 14 years

(Cl. D34—5)

To all whom it may concern:

Be it known that I, William E. Doherty, a citizen of the United States of America, residing at Chicago, in the county of Cook and State of Illinois, have invented a new, original, and ornamental Design for a Punching Bag, of which the following is a specification, reference being had to the accompanying drawing, forming part thereof.

Fig. 2 is a top view thereof.

I claim:

The ornamental design for a punching bag, as shown.

WILLIAM E. DOHERTY.
